UNITED STATES PATENT OFFICE.

MICHAEL A. BLODGETT, OF DULUTH, MINNESOTA.

DESIGN FOR A FRUIT AND VEGETABLE KNIFE.

49,252.

Specification for Design.

Patented June 27, 1916.

Application filed April 16, 1915. Serial No. 21,928. Term of patent 7 years.

To all whom it may concern:

Be it known that I, MICHAEL A. BLODGETT, a citizen of the United States, residing at Duluth, in the county of St. Louis and State of Minnesota, have invented a new, original, and ornamental Design for Fruit and Vegetable Knives, of which the following is a specification, reference being had to the accompanying drawing, forming part thereof.

The figure is a perspective view of a fruit knife, showing my new design.

I claim:

The ornamental design for a fruit and vegetable knife, as shown.

MICHAEL A. BLODGETT.
